AUTOMATIC FLOW CAP

Sam Edson Tobey, Kalamazoo, Mich.

Application December 23, 1936, Serial No. 117,321

2 Claims. (Cl. 15—133)

This invention relates to an automatic flow cap for bottles and the like.

The main objects of this invention are to embody in such a cap a free flowing automatic liquid spreading means adapted to be attached to the mouth of the container; to provide such a cap of invertible design for bottles and the like; to provide a clearing and cleaning rod for such a device; and to provide a device of this character which shall be simple in construction and operation and inexpensive to manufacture.

This invention is illustrated by the accompanying drawing in which:

Figure 1 is a side elevation of a bottle with my improved cap in its sealing closure position thereon.

Fig. 2 is a side elevation of the cap plug and attached clearing and cleaning rod.

Fig. 3 is a side elevation of the cap with its tube and liquid spreading means.

Fig. 4 is mainly an axial section of my improved device in operative position; the bottle being shown in dotted outline with a part broken away.

Figs. 5 and 6 are axial sections of modified forms of my improved cap and spreading means.

Here my improved cap and spreader device comprises a cylindrical shell 1 of Bakelite or the like, provided with internal threads 2 and 3 and a medial transverse wall 4 integral therewith.

This wall 4 has a central perforation 5 into which one end of a tube 6 is set. The seating of said tube in said wall may be by any convenient method and means, as by simply wedging or forcing it therein, as shown in Fig. 4. The other end of tube 6 is provided with a liquid spreading means

such as a sponge 7 or the like which is secured in any convenient manner as by forcing the sponge over the prongs 8 formed on said tube by splitting the end thereof medially and spreading the resultant prongs in the manner shown in Fig. 4.

A pocket 9 is provided in sponge 7 adjacent the tubular opening 6.

A cleaning and clearing rod 10 of smaller diameter than the inner circumference of the tube 6 is adapted to be inserted in said tube when the device is not in use. One end of this rod is set coaxially in a plug 11 which is externally threaded to fit in one end of cap shell 1. This plug has an end flange 11' to overlap the end of shell 1 to facilitate application of turning force.

In non-use shell 1 is threaded onto the usual externally threaded neck 12 of a bottle 12' by employing the end of said shell containing the threads 2. The tube 6 will then be in the bottle. The rod 10 is then inserted into the tube 6 and

the plug 11 turned home in the threads 3 of the shell 1. The device is then in non-use and inoperative or sealed as illustrated in Fig. 1.

In adjustment for operation, the plug 11 is unscrewed at 3 from the shell and with rod 10 is removed and laid aside. The shell 1 is then also unscrewed from the bottle 12; inverted or turned upside down, and screwed on the bottle by means of shell threads 3.

Figure 4 shows the liquid spreading unit ready for operation. In use the bottle is grasped in the hand and the sponge 7 applied to the surface to be operated upon. In so doing the bottle is tilted so as to cause the liquid in the bottle to flow outwardly therefrom through the tube 6 to the sponge. When the operator has finished using the device, the shell 1 is unscrewed and inverted, the tube 6 is inserted in the bottle, and the shell threaded on the neck of the bottle. The rod 10 is then inserted in the tube 6, forcing all liquid adhering to the walls of the tube back into the bottle, thereby cleaning and clearing the passageway 6'. When the plug 11 is screwed into the shell 1, employing the shell threads 3, the bottle will be in condition to be transported or laid away with the contents thereof sealed in the bottle.

It will be noted that the rod 10, when in place, extends beyond the lower end of the tube and projects into the pocket 9 of the sponge whereby it insures, upon removal, an ample passageway for the liquid.

Figure 4 shows in shell 1 a pair of gaskets 13—13 one on each side of the partition 4 to insure against leakage.

Fig. 5 shows a modified form of my invention wherein the shell 1' is internally threaded throughout its length, and the separately formed screw wall 4' having external threads is anchored in place by pins 14.

In the spreading means shown by Fig. 6 a brush 15 is secured to the tube 6 by bending, or spinning, the edge 16 thereof back and then forward upon itself and pressing the edges toward the tube wall where, being set, they hold the bristles of the brush arranged cylindrically on the tube. The liquid flowing through the tube then enters the center of the brush.

It is to be understood that some of the details set forth may be altered or omitted without departing from the spirit of the invention as defined by the following claims.

I claim:

1. A bottle closure and liquid dispenser comprising an internally threaded cylindrical shell 55

to receive the mouth of the bottle and having a
perforated medial transverse wall, a tube having
one end set in the perforation in said wall and
having on its opposite end means adapted for
spreading liquid emitted through said tube, in
combination with an externally threaded plug to
fit in said shell and having an elongated clean-
ing rod mounted centrally therein and adapted
to be inserted and housed in said tube when the
device is adjusted for non-use.

10 2. In a device of the class described compris-

ing an internally threaded cylindrical cap for
bottles and the like, a wall disposed medially
across said cap and having a central discharge
feed aperture, an elongated tube one end of which
is set in said feed aperture, a liquid-spreading 5
means on the opposite end of said tube, and a
cleaner and stopper element adapted to be in-
serted in said tube for clearing the passage there-
in, and to act as a closure for said bottle and
tube.

10 SAM EDSON TOBEY.
